UNITED STATES PATENT OFFICE.

JOHN H. ALLEN, OF VERONA, NEW JERSEY.

INSULATED RAIL-JOINT.

1,110,098.

Specification of Letters Patent. Patented Sept. 8, 1914.

Application filed November 18, 1911. Serial No. 630,522.

To all whom it may concern:

Be it known that I, JOHN H. ALLEN, a citizen of the United States, residing at Verona, in the county of Essex and State of New Jersey, have invented certain Improvements in Insulated Rail-Joints, of which the following is a specification.

The objects of this invention are to provide in an insulated joint for railways filler angles adapted at their top and bottom edges to directly engage the head and base flanges of the rail ends, and to combine with such filler angles connecting plates having vertical portions which receive at their upper edges the load from the rail directly; to this end to provide connecting plates with vertical portions which engage beneath outwardly projecting heads of the filler angles and have their outer surfaces substantially in the vertical planes of the outer edges of said heads; to provide connecting plates having base portions beneath the rail ends, and suitable connecting portions between said base portions and vertical portions; to form such a joint of a filler angle which also has a base providing an outer bearing surface and a connecting plate whose vertical portion also engages said base at its lower edge; to thus secure a base-supported insulated joint of great firmness and strength; to secure parts of simple construction which can be readily rolled, and to obtain other advantages and results as may be brought out in the following description.

Referring to the accompanying drawings, in which like numerals of reference indicate the same parts throughout the several views, Figure 1 is a cross-section of a joint of my improved construction, taken through one of the bolts, as on line A—A, Fig. 2; Fig. 2 is a plan of a portion of the joint, partly in section on line B—B, Fig. 1, to show the arrangement of filling angles and insulation; Fig. 3 is a perspective view of a preferred form of filler angle, on small scale; Fig. 4 is a side view of the insulating end post which is placed between the ends of the rails also reduced; Fig. 5 is a cross-section of a joint illustrating certain modifications in the bases of the connecting plates; Fig. 6 is a side elevation of a portion of a joint with connecting plates having such modified bases; Fig. 7 is a side view of a portion of a connecting plate having a further modified base, and Fig. 8 is an end view of the same.

In said drawings 1, 1 indicate two adjacent rail ends in a track, which are united by my improved joint, said rails having the usual head 2, web 3 and base 4. The members of the joint upon one side of the rail ends are just like those upon the other side, and hence a description of the construction of one will suffice for both.

Against the side of each rail end, and not extending beyond the extremity of that rail end, is a filler angle 5, adapted to fit between the head and base of the rail. Said filler angle 5 has a web 6, and at the top of said web is a sort of head 7 which provides an upwardly facing bearing surface 8 adapted to engage the under surface 9 of the head of the rail, while at the bottom of the filler angle is preferably an enlarged base 10 providing a broad bearing surface 11 adapted to engage the top of the base flange of the rail. Obviously these bearing surfaces converge toward the rails and are adapted to wedge against the head and base flange of the rail. Said head 7 and base 10 of the filler angle project outwardly from the web 6, or away from the rail, and provide opposite facing bearing surfaces 12 and 13, the upper bearing surface 12 facing downwardly and being preferably inclined slightly upward and outward, and the lower bearing surface 13 facing upward and being inclined downwardly outward, as shown. The webs 6 of these filler angles are adapted to receive the transverse bolts 14 which bind the joint together, and preferably have for this purpose a slot 15, as shown in Fig. 3, so as to allow for different spacings of bolt holes in rails.

Between the extremities of the rails 1, 1 is placed an end post 16 of insulating material, shown in detail in Fig. 4, said post being of such shape as to substantially register at its top and bottom edges with the top and bottom of the rails and at its side edges with the outer surfaces of the filler angles 5, 5. Insulating plates 17, 17 are arranged one on each side of the joint outside the filler angles 5, 5 and extending longitudinally for the length of both filler angles, as indicated in Fig. 2. This insulating plate is of any material suitable for the purpose, and is shaped transversely to fit against the filler angles, having upper and lower parts 18, 19, respectively, adapted to fit against the upper and lower bearing surfaces of the filler angles, an intermediate

portion 20 to lie against the webs of the filler angles, and a base portion 26 extending out over the base flange of the rail, as at 25, and in under the same. Said web 20 receives the bolts 14, and upon said bolts are arranged the usual insulating bushings 21 and washers 22.

Outside the insulating plate 17 is the real connecting means of the rail joint, and it is a feature of my invention that the connecting plates used for this purpose have vertical portions engaging beneath the heads 5 of the filler angles with their outer sides substantially in the planes of the outer edges 15 of said heads, whereby they take the load from the rail directly.

In Figs. 1 and 2 I have shown connecting plates the vertical portion of each of which has upper and lower bearing surfaces which converge inwardly toward the rail ends and are adapted to engage the corresponding bearing surfaces of the filler angle. Said connecting plates are furthermore of the continuous type, each with a base portion 27 adapted to underlie the base of the rail ends, said base portion being connected to the vertical portion by an intermediate portion which extends vertically upward from the base portion and then inclinedly upward and inward to the lower edge of the vertical portion, as shown. The base portions 27 contact with the lower bearing surfaces 24 of the connecting plates to exert a wedging effect upon the base of the rail ends, when the transverse bolts 14 are tightened up, and thus give said base a firm and solid support.

In Figs. 5 and 6 I have shown connecting plates 36 having their upper portions substantially as shown in Figs. 1 and 2 and their base portions having beneath the end post 37 or meeting point of the two rail ends, each a reinforcing member 38. This reinforcing member comprises a downward extension or rib 39 at the outer edge of the base portion and longitudinally thereof which extension or rib has perforations to receive bolts 40, extending through both reinforcing members of the rail joint and preferably lying close to the under surface of the base portions of the connecting plates, as shown. Preferably, webs 41, 41 extend from the ends of the extension or rib 39 of each reinforcing member, and integral therewith, transversely across the under surface of the base portions. These webs 41 are preferably of the same height as the extension or rib 39 at their junction therewith, and sloped from such height to substantially nothing at their opposite ends, as shown.

Other modifications in the form and construction of the connecting plates might be made without departing from the spirit and scope of the invention, so long as they have each a base portion and a vertical portion which bears wedgingly at its upper edge be-

neth the head of the filler angle and has its outer side substantially in the vertical plane of the outer edge of said filler angle head, and I do not wish to be understood as restricting myself to other features and details except as required by the following claims when construed in the light of the prior art.

Having thus described the invention, what I claim is:

1. In an insulated rail joint, the combination with meeting rail ends, of filler angles on opposite sides thereof each having a vertical web adapted to rest at its lower edge on the rail base and having at its upper edge a head with a bearing surface which slopes inwardly toward the rail ends and is adapted to wedge beneath the head of the rail, said head of the filler angle projecting outwardly from its said web away from the rail and providing an under bearing surface which also slopes inwardly toward the rail ends, insulating plates outside said filler angles extending over the said last-mentioned bearing surfaces and beneath the rail ends, connecting members overlapping the meeting rail ends each having a vertical portion adapted to bear at its upper edge against said under bearing surface of a filler angle head with its outer side substantially in the vertical plane of the outer edge of said head, each connecting member also having a base portion adapted to extend under the rail ends, and means for clamping the rail ends between said filler angles insulating plates and connecting members.

2. In an insulated rail joint, the combination with meeting rail ends, of filler angles on opposite sides thereof each having a vertical web adapted to rest at its lower edge on the rail base and having at its upper edge a head with a bearing surface which slopes inwardly toward the rail ends and is adapted to wedge beneath the head of the rail, said head of the filler angle projecting outwardly from its said web away from the rail and providing an under bearing surface which also slopes inwardly toward the rail ends, insulating plates outside said filler angles extending over the said last-mentioned bearing surfaces and beneath the rail ends, connecting members overlapping the meeting rail ends each having a vertical portion adapted to bear at its upper edge against said under bearing surface of a filler angle head with its outer side substantially in the vertical plane of the outer edge of said head, each connecting member also having a base portion adapted to extend under the rail ends and an intermediate portion extending vertically upward from said base portion and then inclinedly inward and upward to the lower edge of the web, and means for clamping the rail ends between said filler angles insulating plates and connecting members.

3. In an insulated rail joint, the combination with meeting rail ends, of filler angles on opposite sides thereof each having a vertical web with a head and base at its upper and lower edges respectively providing bearing surfaces which converge inwardly toward the rail ends and are adapted to engage the head and base of the rail, respectively, said head and base of the filler angle projecting outwardly from its said web away from the rail and providing facing bearing surfaces which converge toward the web, insulating plates outside said filler angles extending over said last-mentioned bearing surfaces, connecting members overlap ping the meeting rail ends each having a vertical portion adapted to bear at its upper and

lower edges against said last-mentioned outer bearing surfaces of a filler angle with its outer side substantially in the plane of the outer edges of the head and base thereof, each connecting member also having a base portion adapted to extend under the rail ends and an intermediate portion extending vertically upward from said base portion and then inclinedly inward and upward to the lower edge of the web, and means for clamping the rail ends between said filler angles insulating plates and connecting members.

JOHN H. ALLEN.

In the presence of—

FRANCES E. BLODGETT,
CORNELIUS ZABRISKIE.
